UNITED STATES PATENT OFFICE.

JOSEPH B. SARGENT, OF NEW HAVEN, CONNECTICUT.

DESIGN FOR DRAWER-PULL.

Specification forming part of Design No. 5,192, dated August 8, 1871.

To all whom it may concern:

Be it known that I, JOSEPH B. SARGENT, of New Haven, in the county of New Haven and State of Connecticut, have invented a new Design for Drawer-Pull; and I do hereby declare the following, when taken in connection with the accompanying drawing and the letters of reference marked thereon, to be a full, clear, and exact description of the same, and which said drawing constitutes part of this specification and represents a front view.

This invention relates to a design for the article of manufacture known to the trade as drawer-pulls—that is to say, a device to be secured to the front of the drawer and having a recess for the insertion of the fingers for the purpose of opening the drawer, the same device being often used as a lifting-handle; and the invention con-

sists in the peculiar form of the pull, as more fully hereafter described.

The pull is formed with four trapezoidal surfaces, one forming the top, another the front, the two others the ends. From the two ends projections extend for the insertion of the screw, by means of which the pull is secured. These surfaces may be ornamented according to the taste of the manufacturer or requirements of the trade, such ornamentation being no part of the design.

I claim as my invention—

The design for drawer-pull, as herein described and shown.

JOSEPH B. SARGENT.
